GAME

John L. McKeown, Winnetka, Ill.

Application November 12, 1940, Serial No. 365,294

7 Claims. (Cl. 273—123)

The invention relates to an improvement in games and has for its primary object the provision of an improved game operating by chance which is of simple construction and amusing in use.

Other objects will appear hereinafter.

The invention consists of the combinations and arrangements of parts hereinafter described and claimed.

The invention will be best understood by reference to the accompanying drawings forming a part of this specification and in which—

Figure 1 is a top plan view of a game board embodying the invention;

Figure 2, a section thereof taken substantially on line 2—2 of Figure 1;

Figure 3, an enlarged section taken substantially on line 3—3 of Fig. 1;

Figure 4, an enlarged detailed section taken substantially on line 4—4 of Figure 1;

Figure 5, a side view of one of a plurality of partitions employed in the game;

Figure 6, a top plan view corresponding with Fig. 5;

Figure 7, a top plan view shown partially in section of the marker employed in the construction;

Figure 8, a side view of said marker;

Figure 9, a side view of another form of marker employed in the game;

Figure 10, a face view of said last mentioned marker;

Figures 11, 12 and 13 are side views respectively of additional markers employed in the game;

Figure 14, a side view of another form of partition employed in the game;

Figure 15, an end view of the partition shown in Fig. 14;

Figure 16, a top plan view of a modified form of game board;

Figure 17, a side view of a modified form of partition employed of the game board shown in Figure 16;

Figure 18, an end view of the partition shown in Fig. 17;

Figure 19, a section taken substantially on line 19—19 of Fig. 1, and

Figure 20, a section of a spinning ball-projecting top employed in the game.

The embodiment of the invention illustrated in Figs. 1 to 15 of the drawings comprises a game board made in two adjustable parts. One of these parts 20 is provided at one edge with an upwardly extending retaining wall 21, and on its

bottom with downwardly extending feet 22 which are adapted to maintain the board in substantially level condition. Guide channels 23 are arranged under the ends of the board part 20, and bars 24 attached to the other board part 25 are arranged to slide in the channels 23 so as to render the game board laterally adjustable in size. The board part 25 is provided with an upstanding retaining wall 26 along its inner edge adapted and arranged to cooperate with the retaining wall 21 on the other board part. Flexible end retaining walls 27 are provided at their ends with spring clips 28 which frictionally and adjustably engage the walls 21 and 26 to cooperate therewith to form an enclosure.

If desired, the top face of the board part 20 and the inner face of the walls 21 and 27 may be ornamented to imitate a race track.

20 The board part 25 is provided with a downwardly and inwardly extending extension 29 forming a pocket 29' adapted and arranged to receive a racing program 31 or the like, and a leaf spring 30 is arranged as indicated in the pocket 29' to frictionally retain such a folded program therein. The arrangement is such that an ordinary race track program may be folded and inserted in the pocket 29' with its list of entries for any given race exposed in the space 25 between the board parts 20 and 25 as indicated.

25 A plurality of partitions 32 are provided for dividing the spaces on such a program to correspond with the entries thereon. To this end each of the partitions 32 is provided at its outer 30 end with a spring clip 33 adapted and arranged to embrace the wall 26, and in its inner end with a projection 34 adapted and arranged to slideably engage a guide channel 35 mounted on the adjacent edge of the board part 20 as indicated in Fig. 2, and whereby said partitions 32 may be readily arranged for the purpose indicated. Preferably each of the partitions 32 is provided with an outline figure of a race horse 36 as shown.

45 A spinning top 37 which is adapted and arranged to contain a ball 38 as its spinning point and is equipped with a spring detent 39 adapted to release said ball when the top ceases spinning and falls onto board part 20, is provided for projecting the ball projectile 38 over the top of the board part 20 and into the spaces or pockets between the partitions 32. The spinning top 37 is fully illustrated and described in Patent No. 2,220,823 granted me on November 5, 1940 and 50 requires no further description here.

I also provide a number of deflectors 40, each equipped with one of the spring clips 33 and the projection 34 whereby the same may be readily secured in one of the pockets between the partitions 32. Each deflector is provided at its inner end with an arcuate channeled central part 41 and with laterally extensible side parts 42, by means of which the deflector may be adjusted to fit the varying width of the pockets between the partitions 32. Each of the partitions 40 is also provided with the word "scratched" in outline as best shown in Fig. 8. By this arrangement when any of the horses listed for any particular race are "scratched" or withdrawn from the race, one of the markers 40 may be inserted in the corresponding pocket to so indicate and the deflector 41-42 will prevent the entry of a ball to that pocket.

By this arrangement an interesting game of chance may be played in conjunction with an ordinary race track program. The program is first folded to cause the column giving the entries for any particular race to be exposed on top, and then the program is inserted in the pocket 29 and partitions 32 adjusted to form pockets over each entry in the race. Then the top 37 is spun upon the board 20 and the ball projectile 38 projected therefrom to enter one of the pockets between the partitions 32 which will thereby select by chance one of the horses in the race. Another player could similarly spin the top and similarly select the same or another horse as his choice to win the race, and thus each of the group could so select by chance a horse to win in the particular race. Then by comparison with the actual results of the race the winner of the chance contest could be thus determined.

I also provide a plurality of numbered markers 44 in the form of spring clips, as best shown in Figs. 9 and 10, and these markers may be slipped over the clips 33 of the partitions 32 and thus identify the pockets between said partitions. An interesting game could also be played by the use of these markers 44. After each of the pockets between the partitions 32 is thus marked or given a number, each player by spinning the top 37 and thus projecting the ball 38 into one of the pockets will acquire the number of the pocket as the value for his play; the sum total of the numbers thus acquired by any player after a series of manipulations of the top 37 will constitute his total score for that game.

Another series of deflectors 45 are also provided, each equipped with a spring clip 33, a projection 34 and a deflector 41-42. The deflectors 45 are marked with the words, "first," "second" and "third," and these deflectors may also be used in conjunction with the game first described where a single player is using the board. In this game the player spins the top three times, inserting one of the deflectors 45 in the first, second and third pockets thus selected and whereby the names of horses may be selected by the player by chance to finish in the race either first, second or third. By comparing the chance selections made with the actual results of the race, the player registers a score to correspond, as will be readily understood.

A set of partitions 46, each bearing the representation of a dog 47 is also provided so that the same game may be played conveniently in conjunction with the dog race instead of horse race, as will be readily understood.

In the modified form of construction illustrated in Fig. 16 separate end walls 48 are provided for

adjustable attachment to the walls 21 and 26 as indicated, and the top surface of the board part 20 and the inner faces of the walls 21 and 48 may be ornamented in imitation of a Jai-alai court.

5. Partitions 49 bearing the representation of a Jai-alai player 50 are provided for use in conjunction with a folded Jai-alai program in which the various players are listed and whereby the pockets between the partitions 49 may be correspondingly employed in conjunction with the game of Jai-alai as will be readily understood.

While I have illustrated and described the preferred forms of construction for carrying the invention into effect, these are capable of variation and modification without departing from the spirit of the invention. I therefore do not wish to be limited to the precise details disclosed but desire to avail myself of such variations and modifications as fall within the scope of the appended claims.

I claim:

1. A game board comprising two parts connected for adjustment toward and from each other, a retaining flange upstanding from each part and arranged in spaced parallel relation, and a pair of flexible retaining walls having their opposite ends adjustably connected with said first retaining walls and defining therewith a variable playing space while permitting relative movement of said first retaining flanges as occasioned by adjustment of said parts.

2. A game board comprising a relatively wide rectangular section having an upstanding retaining flange at its outer edge, a relatively narrow rectangular section parallel to and in spaced relation to the inner edge of said first section and having an upstanding retaining flange on its inner edge, slidable connections between said sections for adjustment thereof toward and from each other, and a pair of retaining walls arranged in spaced relation between said first and second retaining walls and having their opposite ends adjustably connected therewith, said first, second and last retaining flanges defining a variable playing space on the board.

3. A game board according to claim 2 wherein said last named retaining walls include arcuate flexible sections concavely opposing each other on the first named board section, and spring clips on the ends of the last named retaining walls for frictional and adjustable connection with said first and second retaining flanges.

4. A game board according to claim 2 together with a rectangular extension from said second board section underlying the space between the first and second board sections for supporting a racing program with entries thereon, and partitions releasably and adjustably connected with the retaining flange on the second board section providing spaces between the board sections corresponding with the entries on the racing program.

5. A game board comprising a relatively wide main rectangular section, a supplemental relatively narrow rectangular section parallel with and in spaced relation to the first section, slidable connections between the sections for adjustment thereof toward and from each other, the second section being extended on an outer vertical flange and a relatively wide horizontal extension underlying the space between the first and second sections and defining a pocket beneath the second section for receiving the edge of a racing program and a support for the body portion of the program for providing a floor between the sections,

and partitions extending across the space between the sections above the program support and removably and adjustably connected with the second section.

6. A game board according to claim 5 together with deflector members adjustably and removably supported by the second section for closing the entrance ends of spaces defined by pairs of partitions adjacent the first section.

7. A game board according to claim 5 wherein each board section is provided with an upstanding retaining wall with said walls in spaced parallel relation, and a pair of retaining walls between and generally transverse to the first walls and having their opposite ends removably and adjustably connected therewith.

JOHN L. McKEOWN.
